(21) Appl. No.: **29/304,943**

(22) Filed: **Mar. 11, 2008**

(57) **CLAIM**

The ornamental design for a head light for a motorcycle, as shown and described.

DESCRIPTION

FIG. 1 is a front elevational view of a head light for a motorcycle showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a perspective view thereof.

The broken line showing of the environment is for illustrative purposes only and forms no part of the claimed design.

The portion encompassed by a solid line is the design sought to be patented.
